UNITED STATES PATENT OFFICE.

ELMER ERWIN, OF VALLEY POINT, PENNSYLVANIA.

LOCK-NUT.

1,070,789.

Specification of Letters Patent. Patented Aug. 19, 1913.

Application filed November 19, 1912. Serial No. 732,316.

To all whom it may concern:

Be it known that I, ELMER ERWIN, a citizen of the United States, residing at Valley Point, in the county of Huntingdon and State of Pennsylvania, have invented new and useful Improvements in Lock-Nuts, of which the following is a specification.

This invention relates to an improvement in lock nuts and designed particularly to provide a nut which may be readily locked against accidental unscrewing and which through a suitable manipulation of the locking means may be as readily and conveniently removed as an ordinary nut.

The invention in its preferred form of details will be described in the following specification, reference being had to the accompanying drawing, in which—

Figure 1 is a vertical sectional view through my improved lock nut showing the same applied to a bolt, Fig. 2 is a bottom plan view of a lock nut showing the locking member in one position, Fig. 3 is a similar view showing it in the opposite position, and Fig. 4 is a vertical central section through the nut.

In the drawings, the improved nut 1 is formed with a usual threaded bore 2 and for the purposes of the present invention this bore is circumferentially enlarged from one face of the nut for a portion of its depth to provide a chamber 3 the wall of which is plain or unthreaded. Through the wall of the chamber 3 is a transversely arranged opening 4 which at its outer end communicates with a channel 5 formed in the side of the nut, this channel extending longitudinally or in parallelism with the bore of the nut.

The locking member 6 is provided of peculiar construction, said member comprising a single length material, including a shank having its inner end of spring material and projected at an angle to the main length of the bar, the inner terminal 7 of the member 6 forming an engaging point. The end of the locking member opposite the spring point is bent laterally, as at 8, being of a size to fit in the channel 5. The locking member is passed through the opening 4 in the wall of the nut and with its laterally bent end 8 resting in one end of the channel 5 the spring point will overlie the bore of

the nut. The bolt 9 is formed with longitudinal channels 10 one wall of which is arranged radially of the bolt and the other wall inclines with relation thereto, the radially exposed wall forming a stop. In use it will be obvious that with the projecting portion 8 of the locking member disposed in the channel 5 that the free terminal of said projecting member extends toward the head of the bolt, the spring point of the locking member will in the turning of the nut on the bolt override the grooves therein but through engagement of the spring terminal and one of the shoulders of the groove will prevent the reverse movement of the nut. When it is desired to remove the nut the locking member is drawn outwardly, the spring portion permitting such movement and the portion 8 reversed, that is, arranged with such portion 8 thereof in the opposite end of the channel. In this position it will be obvious that a free unscrewing of the bolt is permitted, the spring point now overriding the radial shoulders of the grooves in the bolt in a reverse direction.

The improved bur is of similar construction and the locking means described may be readily applied to any type of bur or nut in use. The locking member is to be made of a single length of material of sufficient strength to resist accidental turning of the bur and at the same time to prevent breakage through strain on the parts.

What is claimed is:

A locking nut having an enlarged chamber concentric with the bore, a locking member projection through the chamber and having a terminal offset spring point to engage longitudinal channels in the bolt, the outer end of the locking member having a lateral projection adapted to be disposed in either of two positions in the channel formed in the outer surface of the nut to reverse the locking effect of the spring point of said member with respect to the longitudinal channels in the bolt.

In testimony whereof I affix my signature in presence of two witnesses.

ELMER ERWIN.
